DESIGN FOR A HOLDER FOR SHAVING OUTFIT OR SIMILAR ARTICLE

Eleanore Groos, Bronxville, N. Y., assignor to Cooper & Cooper, Inc., Brooklyn, N. Y., a corporation of New York

Application August 7, 1935, Serial No. 57,990

Term of patent 3½ years

To all whom it may concern:

Be it known that Eleanore Groos, a citizen of the United States and resident of Bronxville, in the county of Westchester and State of New York, has invented a new, original, and ornamental Design for a Holder for Shaving Outfit or Similar Article, of which the following is a specification, reference being had to the accompanying drawing, forming part thereof, in which, the figure is a perspective view of a holder for shaving outfit or similar article embodying my new design, the opposite sides of said holder (not shown) being like that shown in the drawing.

I claim:

The ornamental design for a holder for shaving outfit or similar article, substantially as shown and described.

ELEANORE GROOS.
